ATTORNEY.

UNITED STATES PATENT OFFICE.

ANDREW G. FOLEY, OF EAST HARTFORD, CONNECTICUT, ASSIGNOR OF ONE-HALF TO JOSEPH R. CARROLL, OF EAST HARTFORD, CONNECTICUT.

DETECTOR-BAR FOR RAILROAD-SWITCHES.

No. 902,066.

Specification of Letters Patent.

Patented Oct. 27, 1908.

Application filed December 9, 1907. Serial No. 405,682.

To all whom it may concern:

Be it known that I, ANDREW G. FOLEY, a citizen of the United States, and resident of East Hartford, in the county of Hartford and State of Connecticut, have invented certain new and useful Improvements in Detector-Bars for Railroad-Switches, of which the following is a full, clear, and exact specification.

- 10 This invention relates to railroad switches, and more particularly to the so-called "detector-bars" which are disposed alongside of the rails at cross-overs and connected with the switch-throwing mechanism so as to prevent the latter from being operated while a train, or a car is moving or standing on that portion of the track, the detector-bar being usually of a length at least equaling the distance between the trucks of an ordinary car.
- 15 My invention has for its object the improved construction of the detector-bar, *per se*, in order to obviate certain difficulties which have manifested themselves in the course of time.
- 20 Experience has demonstrated that the wear and compression of the rail-tread due to the running of the cars over the same, forms in time a fin on the upper outside edge of the rail, this fin gradually assuming such proportions as to render the vertical and simultaneously-longitudinal movement of the detector-bar impossible, and it becomes therefore necessary to chisel the rail in order to remove the obstructing feature.
- 25 It is the aim of the present invention to obviate the difficulties heretofore encountered, by providing a detector-bar having a rounded edge for contacting with the side of the rail, instead of the usual sharp edge which constitutes the objectionable feature of the bar used heretofore.

The invention has been clearly illustrated in the accompanying drawings, in which

Figure 1 is a side view of a portion of a rail and its co-operative detector-bar, and Fig. 2 represents a cross-section thereof.

In the drawings, the numeral 10 denotes a railroad rail of ordinary construction, having a tread 11 on which the car wheel *w* runs.

Supported on the bottom flange 12 of the rail 10, is a bracket 13 having a fixed stud 14 on which is pivoted an oscillatory lever 15 which is adapted to rest against either one of a pair of abutments 16 provided on the bracket 13 and serving to limit the throw of the lever 15, which constitutes a link for supporting the detector-bar *D*, to which it is attached by a bolt 17. Usually the detector-bar is supported in this manner at a series of points of its length, the several supports being so arranged as to have all the links move simultaneously and keep the upper edge of the detector-bar in parallelism with the rail-tread.

In the present instance the bar *D* is disposed so as to rest with its upper portion against the outer side of the rail 10, and this edge is free from contact therewith and rounded off as shown at *d* in Fig. 2, so that the formation of a fin on the rail tread will not interfere with the arcuate movement of the bar, which is within the reach of the car wheel tread.

From the foregoing it will be understood that the rise and fall movement of the bar during its longitudinal movement will not in any way be impeded except when a car wheel is above the bar.

It should, of course, be noted that the particular form of rounding or perhaps chamfering the contacting edge of the bar may be varied without interfering with the gist of the invention.

I claim:

1. The combination with a rail, of a detector-bar resting against the side thereof and vertically slideable thereon and having its uppermost edge or tread portion free from contact with the rail side.
2. The combination with a rail, of a detector-bar resting against the side thereof and having its rail-contacting edge rounded to avoid sharp contact with the side of said rail.

ANDREW G. FOLEY.
